Patented Dec. 6, 1921.

UNITED STATES PATENT OFFICE.

JOEL R. BELKNAP, OF MIDLAND, MICHIGAN.

VEHICLE ROAD-TRACK.

1,399,043.

Specification of Letters Patent.

Patented Dec. 6, 1921.

Application filed April 4, 1919. Serial No. 287,404.

To all whom it may concern:

Be it known that I, JOEL R. BELKNAP, a citizen of the United States of America, residing at Midland, in the county of Midland and State of Michigan, have invented certain new and useful Improvements in Vehicle Road-Tracks, of which the following is a specification.

This invention relates to improved highway and road construction.

One object of the invention is to provide substantial tracks upon the highway or road to accommodate the traffic thereover, which would be of standard gage, and sufficiently wide to accommodate the wheels of any ordinary vehicle, and which will combine all of the advantages of an entirely surfaced road with but a small portion of the expense.

Another object of the invention is to construct a track so that a filler may be applied therein, such as asphalt or any other suitable plastic material, which will provide a smooth, hard and permanent track or runway, which can be readily removed when worn and fresh material laid therein without disturbing the track proper, and can be quickly and economically done with very little expense and a minimum delay to traffic.

A still further object is to provide track members so shaped that they will form their own individual anchorages, as well as serving to retain the roadway in place.

With the above and other objects in view, the present invention consists in the combination and arrangement of parts herein-after more fully described, illustrated in the accompanying drawings, and more particularly pointed out in the appended claims, it being understood that changes may be made in the size, proportion and minor details without departing from the spirit or sacrificing any of the advantages of the invention.

In the drawing:

Figure 1 is a fragmentary perspective view of my improved track as applied to the ordinary dirt road.

Fig. 2 is a sectional view thereof, showing the method of securing the tracks together.

Fig. 3 is a detail showing the method of connecting the ends of the track members, and

55

Fig. 4 is a section of a concrete roadway showing my improved construction.

Fig. 5 is another section of a concrete roadway showing the track section formed with but a slight depression.

60

In the specification like reference characters refer to like parts in the drawing.

In carrying my invention into practice, I provide a pair of relatively spaced parallel track members indicated by the numeral 1, and formed as shown, the center thereof being concaved to receive the wheels of a vehicle, and the sides or lips of each member being rounded over with an easy curve, each edge or lip projecting downwardly, and at an angle away from the vertical center line of each individual track member, thereby anchoring and maintaining the track in its position regardless of pressure exerted on either side thereof, or the weight of heavily loaded vehicles traveling the roadway.

It will be noted that the track is formed without any sharp edges or corners, and that the outer lip 3 is somewhat longer than the inner lips 2. While this is not necessary where this construction is used in connection with surfaced pavements and roadways, it is very desirable in connection with the so-called dirt roads, as it will tend to maintain the roadbed in place and prevent any washouts, as well as maintaining the tracks in position against lateral displacement.

Roads and pavements of every description and construction are preferably crowned, and in dirt roads especially this is very desirable in order that the water will readily drain from the same. Vehicles customarily travel on this crowned portion and it will be apparent that the tracks will be laid to straddle the crown, being securely tied together by use of the spacer bar members 4, secured to the main members 1 by means of bolts 5 or in any other approved manner, thus forming a saddle which will be difficult to displace under natural conditions.

It will be understood that the track mem-

bers are composed of sections placed end to end and secured together. This can be done in a number of different ways, but I prefer to do this as clearly shown in Fig. 3, by providing a section 6 of the same formation as the main track members 1, the ends of the said memberslapping on the same, and being secured thereto by means of bolts or rivets 7.

In order that these tracks may wear for a long period of time the concaved portion of the track can be filled with an asphalt or other plastic material 8, which will harden and form a smooth surface to be subjected to the wear by the traffic over the road, and when broken or worn to any great extent, it can be easily removed and fresh material applied, and it will be obvious that the track members proper will wear for an indefinite period.

When using this construction in concrete pavements and the like, and especially for city use where pavements are subjected to continuous and heavy traffic, these tracks can be used without a filler, or they can be filled with the same material of which the pavement is constructed, and it will be apparent that it is merely necessary to refill or lay new track members instead of re-surfacing the entire pavement.

I also wish to call particular attention to the shape of the track sections, and it will be observed that they can be readily rolled in the mills owing to the rounded surfaces, and by varying the depth (a) of the track sections, it will be obvious that the moment of inertia of the track sections will be varied accordingly.

By reference to the foregoing description it will be evident that I have perfected a new and improved construction for roadways, pavements and the like, which can be easily and economically manufactured; which can be quickly laid and which will

have a tendency to maintain the roadbed in place.

45

What I claim is:—

1. A vehicle track comprising a pair of spaced apart parallel members, each member being transversely concave at its upper face and intermediate its longitudinal edges to receive vehicle wheels, the edge portions of said members being arched downwardly and outwardly for embedding in the roadway to anchor the member therein, the outer downwardly arched edge portion being of greater depth than the inner edge portion for bracing the member against edgewise displacement incident to lateral thrusts of vehicle wheels thereon, and a filler in said concave portions of the member for engagement with the vehicle wheels to support the same.

2. In a vehicle track, a track member transversely concave at its middle portion and having downwardly arched and diverging lateral lip portions adapted to be embedded in the material of a roadway, the outer lip portion being of greater depth than the inner lip portion for bracing said track member against transverse displacement under lateral stress.

3. A vehicle track comprising a pair of track members, each being transversely concave in cross section and provided with downwardly arched and diverging lateral portions adapted to be embedded in a roadway, and spacer bars secured at opposite ends beneath the intermediate concave portions of the track members and terminating in spaced relation to the outer elongated arched portions, the shorter arched portions being adapted to rest upon the upper surface of said spacer bar whereby to brace the track members.

In testimony whereof I affix my signature.

JOEL R. BELKNAP.
